UNITED STATES PATENT OFFICE.

HENRY G. RUNNE, OF ROCHESTER, NEW YORK, ASSIGNOR, BY MESNE ASSIGNMENTS,
OF ONE-HALF TO CHARLES L. TOWNSEND, OF ROCHESTER, NEW YORK.

TOY VEHICLE.

1,352,835.

Specification of Letters Patent. Patented Sept. 14, 1920.

Application filed January 24, 1919. Serial No. 272,956.

To all whom it may concern:

Be it known that I, HENRY G. RUNNE, a citizen of the United States, residing at Rochester, in the county of Monroe and State of New York, have invented a certain new and useful Improvement in Toy Vehicles; and I do hereby declare the following to be a full, clear, and exact description of the same, reference being had to the accompanying drawings, forming a part of this specification, and to the reference-numerals marked thereon.

My present invention relates to vehicles and more particularly to toy vehicles such as velocipedes and the like and it has for its object to provide a device of this character that can be manufactured very cheaply and made adjustable for children of different sizes. A further object of the invention is to provide a construction that will permit the vehicle to be readily knocked down or folded for shipment and one in which the adjusting devices are so simple as to be readily operated by unskilled persons. To these and other ends the invention resides in certain improvements and combinations of parts all of which will be herein-after more fully described, the novel features being pointed out in the claims at the end of the specification.

In the drawings:

Figure 1 is a side view of a velocipede constructed in accordance with and illustrating one embodiment of my invention;

Fig. 2 is a similar view of the same vehicle in another position of adjustment;

Fig. 3 is a bottom plan view;

Figs. 4 and 5 are enlarged views of part of the adjusting mechanism;

Fig. 6 is a rear view partly broken away and showing the rear axle support in partial section;

Fig. 7 is an enlarged section on the line 7—7 of Fig. 4, and

Fig. 8 is an enlarged section on the line 8—8 of Fig. 4.

Similar reference numerals throughout the several views indicate the same parts.

In the present embodiment of the invention, I have illustrated a three wheel velocipede adapted to be made mostly of wood and propelled by pushing with the feet against the ground while the child is seated upon the vehicle. The body or seat is indicated at 1. It is narrowed at 2 to allow free move-

ment of the legs and enlarged at the front as indicated at 3 where it is pierced by a steering post 4 terminating at the bottom in a fork 5 to receive an axle 6 and front wheel 7. The steering handle 8 may be adjustable in the post 4 and the latter is provided with a plurality of grooved or reduced bearing portions 9 at different heights. The body may be engaged with any one of these bearing portions to change its elevation and in the present instance, a slide 10 held by a catch 11 is provided but these details are not important to the present invention.

The axle 12 for the two rear wheels 13 is carried by a swinging support 14 that is connected to the rear of the body 1 by angular hinge brackets 15 coöperating with slots 16 in the support and pierced by a pintle 17 passing through the support. With a hinge connection of this nature, it is possible, in knocking down the device for shipment, to fold the support 14 flat against the body 1, with or without removing the wheels 13, which makes a very compact arrangement, the steering post 4 also being removed.

As the body is raised and lowered on the steering post 4, as described, it is necessary to also raise or lower the rear end 85 which is done by swinging the support 14 so that it extends at an inclination rearwardly at a greater or less angle and spreading the wheels 13 from the wheel 7. The support is retained in these positions by an adjustable radius rod that connects it with the intermediate portion of the body and which is shown in detail in Figs. 4 and 5. The rod comprises a latch member 18 and a socket member 19. The latch member has a laterally turned forward or upper end 20 that forms a pivot therefor and has a bearing in a bracket plate 21 on the under side of the body, a cotter pin 22 preventing its disconnection. The latch also has a similar laterally turned portion 23 at its other extremity adapted to engage, selectively, with a series of apertures or sockets 24 in the socket member 19. The intermediate portion of the latch member extends through 100 and is slidably guided in a laterally turned portion 25 at the upper end of the socket member 19, the lower end of which socket member is pivoted to the support 14, in the present instance, by being apertured to 110

receive the rear axle 12 at the center of the latter. The pivot 23 and the pivot 20 of the latch member 18 are both made rather loose fit and so is the engagement of the latch 18 in the guide opening 26 of the socket member so that the two members may be deflected laterally as shown in Fig. 5 to disengage the latch member 18 at 23 from any one of the apertures 24 or to engage it with any of them. When so engaged, it is held in such engagement and the members are maintained parallel to form a substantially continuous radius rod by a sliding keeper plate 27 shown in detail in Fig. 8 and having a perforation 28 therein for the latch member 18 and a perforation 29 therein for the socket member 19. The socket member 19 is preferably of flat material, as shown, and the latch member 18 of round material for obvious reasons but the keeper plate fits both very loosely, as shown, so that it may be easily moved by a child without danger of wedging, because of this looseness it may also have a tendency to gravitate down the inclined radius rod to lie in close proximity to the engaging portion 23 and its socket, as shown in Fig. 4, where it can most advantageously perform its function. When a change in the adjustment is to be made it is slid upwardly on the bar 19 to the position shown in Fig. 5 against the laterally turned portion 25 where it does not interfere with the relative inclination of the members in unlocking them from each other.

I claim as my invention:

1. In a vehicle, the combination with a body and a swinging axle support hinged thereto, of a two-part adjustable radius rod connecting the support and body and embodying a latch member pivoted to one element and a socket member pivoted to the other, said members being loosely guided to slide longitudinally one upon the other and loosely pivoted to their carrying elements to have universal movement thereon to permit the latch member to be deflected laterally into and out of locking engagement with the socket member.
2. In a vehicle, the combination with a body and a swinging axle support hinged thereto, of a two-part adjustable radius rod connecting the support and body and embodying a latch member pivoted to one element and a socket member pivoted to the other, said members being loosely guided one upon the other and loosely pivoted to permit the latch member to be deflected laterally into and out of locking engagement with the socket member, and a keeper slidable upon the members toward and from the point of their guiding contact to retain the latch member in locking engagement with the socket member.
3. In a vehicle, the combination with a

body and a swinging axle support hinged thereto, of a two-part adjustable radius rod connecting the support and body and embodying an apertured socket member pivoted to one element and having a laterally turned end portion provided with a guiding opening and a latch member pivoted to the other element and slideable in the guide of the socket member, and having a laterally turned end portion cooperating selectively with the apertures in the socket member, said members being loosely guided one upon the other and loosely pivoted to permit the latch member to be deflected laterally into and out of locking engagement with the socket member.

4. In a vehicle, the combination with a body and a swinging axle support hinged thereto, of a two-part adjustable radius rod connecting the support and body to extend downwardly at an angle from the latter and embodying an apertured socket member pivoted to the axle support and having a laterally turned upper end portion provided with a guiding opening and a latch member pivoted to the body and slideable in the guide of the socket member and having a laterally turned lower end portion cooperating selectively with the apertures in the socket member, said members being loosely guided one upon the other and loosely pivoted to permit the latch member to be deflected laterally into and out of locking engagement with the socket member, and a keeper slideable loosely upon the members to retain the latch member in locking engagement with the socket member, said keeper being adapted to gravitate toward the point of such engagement.

5. The combination with a vehicle body, a supporting wheel frame hinged on said body, and a truss member comprising a part pivotally connected to said body and a part pivotally connected to said frame, a sliding connection between said parts for holding said parts in operative relation to each other, and means securing said parts together to vary the length of said member, whereby the height at which said body is supported may be varied.

6. The combination with a vehicle body, a supporting wheel frame hinged on said body, and a truss member comprising a rod having a fixed pivotal connection with said body, and a bar pivotally connected with the lower portion of said supporting frame, said rod and bar having integral interlocking parts adapted to connect said rod and bar at any one of a plurality of points for increasing or decreasing the length of said truss member to raise or lower said vehicle body.

7. The combination with a vehicle body, a supporting wheel frame hinged on said body, and a truss member comprising a rod having

a fixed pivotal connection with said body, a bar pivotally connected with the lower portion of said supporting frame, a part on said bar in which said rod is slidable lengthwise of said bar, the end of said rod being bent at an angle to the rod and adapted to enter into any one of a plurality of holes in said bar for adjusting the length of said truss member, and means for holding the bent end of said rod in said holes in the bar.

8. The combination with a vehicle saddle, a supporting frame hinged at its upper end to said saddle and provided at its lower end with an axle, and a truss member connecting said saddle and said frame, said truss member including a rod having a fixed pivotal

connection with said saddle, a bar arranged with its widest face in a substantially vertical plane and having a hole at one end through which said axle extends and having its other end bent substantially at right angles to said bar, said bar having a hole in said bent end and having holes at intervals along the length of the bar, said rod passing through said hole in the bent end of said bar and having a portion projecting toward said bar and adapted to enter into any one of said other holes in the bar for adjusting the length of the truss member, and means for releasably holding the end of said rod in said holes in the bar.

HENRY G. RUNNE.
